UNITED STATES PATENT OFFICE.

GUSTAV A. BJORKHOLTZ, OF CHICAGO, ILLINOIS.

LIQUID-DISPENSING DEVICE.

Application filed March 15, 1926. Serial No. 94,943.

This invention provides an article combining a brush and a fountain in a single organization, whereby the brush may be charged with material without requiring a separate holder therefor.

The invention is particularly adapted for tooth and shaving brushes, the handle constituting a reservoir for receiving the dentifrice or the saponaceous agent according to the adaptation of the invention for cleaning the teeth or lathering the face.

While the drawings illustrate a preferred embodiment of the invention it is to be understood that in adapting the means to meet specific needs and requirements, the design may be varied and such other changes in the minor details of construction may be resorted to within the scope of the invention as claimed, without departing from the spirit thereof.

For a full understanding of the invention and the merits thereof, reference is to be had to the following description and the drawings hereto attached in which,—

25 Figure 1 is a perspective view of a tooth brush embodying the invention.

Figure 2 is a central, longitudinal sectional view of the tooth brush illustrated in Figure 1, the interior feeding mechanism being in elevation,

30 Figure 3 is an enlarged sectional view of the feeding mechanism and a portion of the handle, the plunger being in normal position with the air supplying and material feeding ports out of register.

Figure 4 is a view similar to Figure 3, showing the position of the plunger when the air supplying and material feeding ports are in register,

40 Figure 5 is a transverse sectional view on the line 5—5 of Figure 4.

Figure 6 is a similar sectional view on the line 6—6 of Figure 4.

Figure 7 is a detail view showing the invention adapted to a shaving brush, part of the latter being broken away.

Figure 8 is a central longitudinal sectional view of a modified form of tooth brush, and

50 Figure 9 is a transverse sectional view on the line 9—9 of Figure 8.

Corresponding and like parts are referred to in the following description and designated in the several views of the drawings by like reference characters.

The device comprises a handle 1 which is

hollow to provide a reservoir for receiving the dentifrice, saponaceous agent or other material to be dispensed. The handle 1 is closed at one end by means of a cap 2, and a plug 3 is fitted to the opposite end and constitutes a closure therefor as well as supporting means for the brush, whether of a conventional type for cleaning the teeth, or of the form for lathering the face. The numeral 4 designates a tooth-brush, in the back of which is formed a passage 5. The passage 5 terminates a short distance from the inner end of the brush and an opening 6 leads from the inner or forward end of the passage 5 to supply the dentifrice to the bristles 7 or body of the brush. A tube 8 connects at its delivery end with the passage 5 and obtains a snug fit in the plug 3. The tube 8 has a lateral feed opening 9 adjacent the inner side of the plug 3 and the material passes from the handle 1 through the opening 9 and into the tube 8 to be dispensed by the brush. The dispensing tube 8 is fixed and extends within the handle 1 some distance and has openings 10 and 11 at different points in its length for a purpose to be explained hereinafter. A guide tube 12 is fixedly supported within the handle 1 and receives a plunger and the inner portion of the dispensing tube 8. A plug 13 closes the rear end of the guide tube 12 and forms an abutment for a coil spring 14 which is located within the rear portion of the guide tube 12 and normally tends to hold the plunger at its forward position. The plunger comprises a head 15 and spaced concentric portions 16 and 17, the portion 16 being tubular and slidable on the inner or rear end of the dispensing tube 8. The part 17 projects beyond the part 16 and is slidable within the dispensing tube 8 and is provided with a passage 18 from which openings 19 and 20 extend to register with the openings 11 and 10 of the dispensing tube 8 when the plunger is moved rearwardly to the limit of its throw, as indicated most clearly in Figure 4. An opening 21 is formed in a side of the tubular part 16 and registers with the opening 11 of the dispensing tube 8 when the plunger is in the position shown in Figure 4. An opening 22 formed in a side of the guide tube 12 in line with the opening 11 registers with said opening and the opening 21 when the plunger is moved rearward. Figure 4.

A support 23 is secured within the handle

1 in any determinate way and receives the guide tube 12 and is formed in a side with a longitudinal slot 24 to accommodate a pin 25 which is secured at its inner end in the 5 head 15 of the plunger.

A passage 26 is formed in the support 23 and is in communication at its inner end with the opening 22 of the guide tube 12. An opening 27 formed in a side of the handle 10 is positioned to communicate with the passage 26. A slot 28 formed in a side of the handle 1 in register with the slot 24 receives the outer end of the pin 25, a slot 29 formed in a side of the guide tube 12 in position to 15 register with the slot 24 of the support 23 receives the inner end of the pin 25. A support 30 secured within the handle 1 receives the forward end of the guide tube 12 which may be connected thereto in any 20 preferred way.

In the modification shown in Figures 8 and 9, the back of the tooth brush is of sectional formation and comprises the section 31 to which the bristles 7 are attached and the 25 section 32 which is fitted in a recess formed in the top of the section 31. The passage 5 and opening 6 are formed in the section 32 and the dispensing tube 8 extends into the section 32 and is in communication with the 30 passage 5. The section 32 may form a part of the plug 3 and has a projection 33 at its forward end to enter a socket at the forward end of the recess of the section 31. The section 31 is detachable from the section 32 and 35 is provided at its rear end with a projection 34 to enter an opening formed in the rear end of the section 32 adjacent the handle 1.

The handle 1 constituting the reservoir is adapted to be supplied with the dentifrice, 40 saponaceous agent or other material by removing the cap 2 and after the handle has been charged the cap 2 is replaced. The interior parts normally occupy the position shown most clearly in Figure 3, wherein the 45 several openings or ports are out of register, thereby preventing any discharge of the material from the reservoir. To supply the brush, the plunger is moved rearward by engaging a digit of the hand with the projecting end of the pin 25 and moving the same to the rear end of the slot 28, as indicated most clearly in Figure 4. The article is held in upright position to insure an outflow of the material from the handle to the brush. 50 When the plunger occupies the position indicated in Figure 4, the spring 14 is compressed and the several openings or ports register so that air enters the opening 27 and passes to the interior of the handle 55 through the openings 26, 22, 21, 11, 19, 18, 20 and 10. At the same time the material from the reservoir of the handle flows through the opening 9, tube 8, passage 5 and opening 6 to the brush. After the brush has 60 received the required amount of material the

pin 25 is released and the spring 14 moves the plunger forwardly to the position indicated in Figure 3, thereby throwing the several openings or ports out of register and cutting off the discharge of the material. 70 The portion 17 of the plunger in which the passage 18 is formed constitutes in effect an air supplying tube, since the air flows therethrough from the outside to prevent the formation of a vacuum in the reservoir when 75 the plunger is adjusted to effect a feed of the material from the reservoir to the brush. The part 17, by reason of its function, constitutes an air supplying tube and since its forward end is closed or solid and obtains a 80 snug fit within the dispensing tube 8 it also operates as a plunger to positively eject the material should the same be of a viscous nature or tend not to flow readily through the dispensing tube 8 to the brush. 85

Having thus described the invention, I claim:

1. In a dispensing device, a reservoir handle, a guide tube having an air inlet, a dispensing tube within the guide tube provided with air ports and a discharge port for the outflow of the material from the reservoir, one air port being opposite the air inlet of the guide tube and the other beyond the guide tube, and a plunger snugly fitting within the guide tube and having a portion 90 slideable upon the inner end of the dispensing tube, and including an air supplying tube slideable within the inner end of the dispensing tube and having ports to register with the air ports of the dispensing tube in one position of the plunger and in another position of the plunger to move the several ports out of register to cut off the inflow of air and the outflow of the material from 95 the reservoir. 100

2. In a dispensing device, a reservoir handle, a guide tube fixed within the reservoir and having an air inlet, a fixed dispensing tube within the guide tube having inlet and outlet air ports and a feed opening, one of the ports registering with the air inlet of the guide tube and the other being beyond the guide tube, an air tube slideable within the inner end of the dispensing tube to cover and uncover the feed opening and provided with inlet and outlet air ports to register with the corresponding ports of the dispensing tube when the feed opening is uncovered, and a plunger slideable within the guide tube and having a portion slideable over the inner end of the dispensing tube and provided with an air opening to register with corresponding air openings of the guide and dispensing tubes, said plunger carrying the 115 said air tube. 120

3. In a dispensing device, a reservoir handle, a dispensing tube therein provided in a side with a feed opening and inlet and outlet air ports, a guide tube having an end portion 130

receiving the inner end of the dispensing tube and spaced therefrom and provided in a side with an air port in line with the inlet air port of the dispensing tube, and a 5 plunger slidable within the guide tube and comprising concentric portions, the outer portion slidably receiving the inner end of the said dispensing tube and having an air port in position to register with the inner 10 air port of the guide and dispensing tubes, and the inner portion being slidable within the inner end of the dispensing tube adapted to close the feed opening thereof and formed with an air passage having inlet and outlet 15 air ports to register with the inlet and outlet air ports of said dispensing tube.

4. In a dispensing device, a reservoir handle, a fixed dispensing tube therein having a feed opening and air inlet and outlet ports, 20 a fixed guide tube having an end portion receiving the inner end of the dispensing tube and provided in a side with an inlet air port, an air tube slidable within the inner end of the dispensing tube and adapted to 25 close the feed opening thereof and provided with inlet and outlet air ports to register with corresponding ports of the dispensing tube, a plunger slidable within the guide tube and having a portion slidable upon the 30 inner end of said dispensing tube and mov-

able with the said air tube, a spring within the guide tube and normally urging the plunger forward and actuating means for the plunger serving to limit the throw thereof in each direction.

5. In a dispensing device, a reservoir handle, a support therein provided with a longitudinal slot and an air opening, a guide tube mounted in the support and provided in a side with a slot and opening to register with the slot and air opening of the support, a plunger slidable within the guide tube and comprising spaced concentric portions, the inner portion constituting an air tube and provided with inlet and outlet air openings, 40 a dispensing tube provided in a side with a feed opening and inlet and outlet air openings in position to register with corresponding openings of the said air tube, and having the inner air tube portion of the plunger 45 slidable therein and adapted to close the feed opening thereof and the outer portion slidable thereover, a pin connected with the plunger and passing through the slot of the guide tube and support, and a spring within 50 the guide tube and normally edging the plunger forward.

In testimony whereof I affix my signature.

GUSTAV A. BJORKHOLTZ. [L.s.]
